(57) **ABSTRACT**

A robotic cleaning device having main body, at least one driving wheel to move the robotic cleaning device across a surface to be cleaned, and a brush for removing debris from the surface to be cleaned. The brush is arranged on a protrusion in a front end portion of the main body. The widest part of the main body is located between the protrusion and the opposite sidewall of the main body, and within the front end portion of the main body.

ROBOTIC VACUUM CLEANER WITH
PROTRUDING SIDEBRUSH

This application is a U.S. National Phase application of PCT International Application No. PCT/EP2013/057815, filed Apr. 15, 2013, which is incorporated by reference herein.

TECHNICAL FIELD

The invention relates to a robotic vacuum cleaner.

BACKGROUND

Robotic vacuum cleaners are known in the art, which are equipped with drive means in the form of a motor for moving the cleaner across a surface to be cleaned. The robotic vacuum cleaners are further equipped with intelligence in the form of microprocessor(s) and navigation means for causing an autonomous behaviour such that the robotic vacuum cleaners freely can move around and clean a space in the form of e.g. a room.

Traditionally, robotic vacuum cleaners have been arranged with circular-shaped main bodies. Such a robot having co-axial drive wheels at the centre of its body has the advantage that it is easy to control and cannot get stuck since it always can rotate 180° and go back the same way it came. However, the circular-shaped main body makes them unsuitable for cleaning corners or edges where a floor meets a wall since these circular vacuum cleaners due to their shape cannot move into a corner or close enough to a wall, or other objects around which cleaning is required such as e.g. chair legs. An example of a robotic vacuum cleaner aiming at solving this problem is disclosed in WO 03/024292, the main body of which at its rear end is circular-shaped, whereas the front end of the main body is substantially rectangular. This is an improvement over the traditional circular-shaped robotic vacuum cleaners in terms of reaching into corners. Further, sweeping brushes are arranged at a bottom side of the main body and disposed such that they are associated with front corner regions of the rectangular-shaped main body front end. However, the robotic vacuum cleaner disclosed in WO 03/024292 still has problems reaching into corners

SUMMARY

An object of the present invention is to solve or at least mitigate a problem of how to provide a robotic vacuum cleaner for navigating corners and turning around in narrow spaces.

This object is attained by a robotic cleaning device comprising a main body, at least one driving wheel arranged to move the robotic cleaning device across a surface to be cleaned, and driving means arranged to control the at least one driving wheel to rotate in order to move the robotic cleaning device across the surface to be cleaned. Further, the robotic cleaning device comprises control means arranged to control the driving means to move the robotic cleaning device across the surface to be cleaned in accordance with navigation information and a cleaning member arranged at a bottom side of the main body for removing debris from the surface to be cleaned, the cleaning member being arranged in a front end portion of the main body, wherein the main body is arranged at the front end portion with a horizontally protruding member on which a brush is arranged.

2

Advantageously, by providing the main body of the robotic vacuum cleaner with the horizontally protruding member and the brush, the robotic cleaning device is capable of reaching into and cleaning corners and other areas where prior art robotic vacuum cleaners cannot reach. Advantageously, the brush which preferably rotates is guided by the protruding member into a corner and moves the debris located out of reach of the cleaning member of the robotic cleaning device such that the debris ends up under the main body and thus can be transported to a dust bag of the robotic vacuum cleaner 10 via the cleaning member 15. Thus, debris and dust located at the very walls and corners can be removed by the robotic cleaning device.

In an embodiment of the present invention, the main body 15 has a front end portion with a front end wall, a rear end portion, a right side wall connecting the front end wall and the rear end portion and a left side wall connecting the front end wall and the rear end portion. The main body thus have a three-lobed shape in this particular embodiment, which is 20 advantageous for moving in and out of corners and navigating narrow spaces like for instance corridors.

In a further embodiment of the present invention, the main body is further arranged such that its width is greatest between an outermost point of the horizontally protruding member and the oppositely located side wall, which greatest width is located at the front end portion of the main body. Since the width of the main body is at its greatest in a lateral direction between the right side wall and the left side wall at the front end portion of the main body, the robotic cleaning device according to embodiments of the present invention can move into a corner and turn the corner to move along an intersecting wall without bumping its rear end portion into the wall leading into the corner. In an embodiment of the present invention, the side walls of the main body are 30 curved. Advantageously, they will thus track the wall leading into the corner when the robotic cleaning device turns the corner and pursues the wall leading out of the corner.

In still another embodiment of the present invention, the cleaning member is arranged adjacent to the front end wall 40 and extending laterally in an opening in the main body along a greater part of the front end wall. Thereby, the robotic cleaning device advantageously cleans an area as wide as possible which contributes to reducing time (and energy consumption) needed to clean a surface.

In yet another embodiment of the present invention, the 45 robotic cleaning device further comprises obstacle detecting means arranged to detect obstacles and provide the control means with the navigation information for enabling navigation of the robotic cleaning device.

In a further embodiment of the present invention, the robotic cleaning device further comprises a flexible bumper enclosing at least the front end portion of the main body. Advantageously, as long as the robotic cleaning device moves forward, the only part of the main body that can run 50 into obstacles is the bumper, implying that collisions with all obstacles can be detected by the bumper. The shape of the main body of the robotic cleaning device as proposed in embodiments of the present invention in combination with appropriate control of the movement of the cleaning device 55 ensures that the robot can maneuver out of all situations when the bumper has detected an obstacle, just like prior art robotic vacuum cleaners having circular-shaped main bodies, and—in contrast to prior art circular-shaped robot cleaners—that corners further can be effectively cleaned.

Further, since the bumper is flexible, it will press resiliently against the front end wall when contacting obstacles, thus mitigating the thrusting effect it has on obstacles in its

way and reducing the risk that the obstacles will be displaced, tipped over and/or be damaged.

Thus, the obstacle detecting means may comprise the flexible bumper and at least one sensor with which the flexible bumper is arranged to cooperate in order to register the robotic cleaning device contacting an obstacle, which sensor is arranged to communicate the navigation information to the control means.

In a further embodiment, an indentation is arranged in the front end portion of the main body adjacent to a respective one of the one or more protruding member(s) and associated brush(es). This is advantageous since the brush can reach around the periphery of smaller obstacles, such as chair legs. By having the indentation enclosing, or at least partly enclosing, the periphery of the smaller obstacles, the area around the obstacles can be more effectively cleaned.

It is noted that the invention relates to all possible combinations of features recited in the claims. Further features of, and advantages with, the present invention will become apparent when studying the appended claims and the following description. Those skilled in the art realize that different features of the present invention can be combined to create embodiments other than those described in the following.

BRIEF DESCRIPTION OF THE DRAWINGS

The invention is now described, by way of example, with reference to the accompanying drawings, in which:

FIG. 1a shows a robotic cleaning device according to an embodiment of the present invention in a top view;

FIG. 1b shows the robotic cleaning device of FIG. 1a in a bottom view;

FIG. 2a shows a robotic cleaning device according to a further embodiment of the present invention in a bottom view;

FIG. 2b shows the contour of the main body of the robotic cleaning device of FIG. 2a in a bottom view;

FIG. 3 illustrates a sequence a-f of movements of the robotic cleaning device of FIG. 2a navigating into and out of two corners in a narrow corridor in a bottom view;

FIG. 4 shows a robotic cleaning device comprising a flexible bumper according to another embodiment of the present invention in a bottom view;

FIG. 5a shows a robotic cleaning device comprising an indentation adjacent to the protruding member according to a further embodiment of the present invention in a bottom view;

FIG. 5b shows the robotic cleaning device according to FIG. 5a when cleaning around small objects in a bottom view; and

FIG. 6 shows a robotic cleaning device according to a further embodiment of the present invention in a bottom view.

DETAILED DESCRIPTION

The invention will now be described more fully herein-after with reference to the accompanying drawings, in which certain embodiments of the invention are shown. This invention may, however, be embodied in many different forms and should not be construed as limited to the embodiments set forth herein; rather, these embodiments are provided by way of example so that this disclosure will be thorough and complete, and will fully convey the scope of the invention to those skilled in the art. All figures except FIG. 1a shows the robotic cleaning device from a bottom perspective.

Directional information, such as e.g. "a right side wall" of the cleaning device should be construed as meaning the side wall on the right hand side of the main body from a top perspective of the cleaning device when viewed from its rear end portion.

The invention relates to robotic cleaning devices, or in other words, to automatic, self-propelled machines for cleaning a surface. The robotic cleaning device according to the invention can be mains-operated and have a cord, be 10 battery-operated or use any other kind of suitable energy source, for example solar energy.

FIG. 1a shows a robotic cleaning device 10 according to an embodiment of the present invention from above, i.e. a top side of the robotic cleaning device is displayed. The 15 robotic cleaning device 10 comprises a main body 11 housing a variety of components as will be discussed in more detail in the following. The main body 11 is further arranged, in a front portion 16, with a horizontally protruding member 33 on which a brush 24 is arranged. Advantageously, by arranging the robotic cleaning device, which in 20 this particular exemplifying embodiment has a circular shape, with a protruding brush 24, its reach will be greatly improved and e.g. corners are much more effectively cleaned.

FIG. 1b shows the robotic cleaning device 10 of FIG. 1a from below, i.e. a bottom view is displayed. The robotic cleaning device 10 comprises a main body 11 housing components such as driving means 29 in the form of an electric motor for enabling movement of the driving wheels 12, 13 such that the cleaning device can be moved over a 30 surface to be cleaned.

In this particular exemplifying illustration, the driving wheels 12, 13 are coaxially arranged along a drive shaft 14. The electric motor 29 is capable of controlling the driving 35 wheels 12, 13 to rotate independently of each other in order to move the robotic cleaning device 10 across the surface to be cleaned. A number of different driving wheel arrangements can be envisaged.

Further, the main body 11 is arranged with a cleaning 40 member 15 for removing debris and dust from the surface to be cleaned. This is in an embodiment of the present invention implemented by means of a suction fan (not shown) creating an air flow for transporting debris to a dust bag or cyclone arrangement housed in the main body via an opening 45 in the bottom side of the main body 11. In a further embodiment, the cleaning member 15 could be embodied in the form of a rotatable brush roll vertically arranged in the opening to enhance the dust and debris collecting properties of the cleaning device 10. The main body 11 may further optionally comprise obstacle detecting means 28 for detecting obstacles in the form of walls, floor lamps, table legs, 50 around which the robotic vacuum cleaning must navigate by having a controller 30 such as a microprocessor control the motor 29 to rotate the driving wheels 12, 13 as required in 55 view of navigation information received by the obstacle detecting means. This will be further discussed subsequently. The obstacle detecting means 28 may be embodied in the form of infrared (IR) sensors and/or sonar sensors, a microwave radar, a camera registering its surroundings, a 60 laser scanner, etc. for detecting obstacles and communicating information about any detected obstacle to the microprocessor 30 in order to have the motor 29 control movement of the wheels 12, 13 in accordance with navigation information provided by the obstacle detecting means 28.

Even though it would suffice to have the cleaning member 65 15, i.e. the opening in the bottom side of the main body 11 via which a suction fan creates an air flow and/or in which

a rotatable brush roll possibly is arranged, arranged in the front end portion 16 adjacent to the brush 24, in an embodiment of the present invention, the opening (and possibly the brush roll) extends laterally in the main body 11 along a greater part of the front end portion 16. Thereby, the robotic cleaning device 10 advantageously cleans an area as wide as possible which contributes to reducing time (and energy consumption) needed to clean a surface. As can be seen in FIG. 1b, the brush 24 is in an embodiment a rotational brush with its centre of rotation arranged on a distance from the main body 11 thus enabling reaching into corners.

FIG. 2a shows a robotic cleaning device 10 according to a further embodiment of the present invention in a bottom view. The robotic cleaning device 10 comprises a main body 11 housing components such as driving means 29 in the form of an electric motor for enabling movement of the driving wheels 12, 13 such that the cleaning device can be moved over a surface to be cleaned.

In this particular embodiment, the main body 11 has a front end portion 16 with a front end wall 17, a rear end portion 20, a right side wall 18 connecting the front end wall 17 and the rear end portion 20 and a left side wall 19 connecting the front end wall 17 and the rear end portion 20. The front end portion 16 of the main body 11 of the robotic cleaning device 10 is the portion of the main body 11 located between drive shaft 14 and a front end wall 17. In an embodiment of the present invention, the front end portion 16 is essentially quadrilateral-shaped, possibly with slightly rounded corners where the front end wall 17 meets the right side wall 18 and the left side wall 19, respectively. The front end wall 17 is flat or slightly curved as shown in FIG. 2a in order to reach far into corners. As previously mentioned, the rotating brush 24 arranged on the protruding member 33 is advantageous for increasing the reach of the robotic cleaning device 10.

In yet a further embodiment, again with reference to FIG. 2a, the main body 11 of the robotic cleaning device is arranged such that its width A is greatest laterally between an outermost point 32 of the horizontally protruding member 33 and the oppositely located side wall 18 (in this case being the left side wall) at the front end portion 16 of the main body, which is illustrated by means of the dotted line. The shape of the main body 11 of FIG. 2a is generally referred to as a three-lobed form. Thus, the width A is the greatest distance measured across the main body 11, advantageously facilitating navigation of corners and narrow spaces such as corridors. Hence, the width A is greater than or equal to width B defined from a rear end portion 20 of the main body 11 to the front end wall 17.

Now, if the greatest width A is located closer to the drive shaft 14, i.e. the greatest width coincides with the rotational axis of the drive shaft 14, it will have the advantage that the geometry of the main body 11 will be adapted to turn around in a narrow space (such as a narrow corridor, as will be illustrated herein below). If on the other hand the greatest width A is located closer to the front end wall, it will have the advantage that the cleaning member 15 can be made as long as possible in a lateral direction of the main body 11. In practice, a compromise can be made by shaping the main body such that the greatest width A is located somewhere between the shaft 14 and the front end wall 17.

In FIG. 2a, the back of the rear end portion 20 is pointed, meaning that the rear end portion 20 is formed by the right side wall 18 and the left side wall 19 connecting at the back of the rear end portion. However, it is possible that the back of the rear end portion 20 alternatively is flat or slightly curved, in which case a rear end wall would connect to the

right side wall 18 and the left side wall 19, respectively, and form the back of the rear end portion 20.

FIG. 2b, shows the robotic cleaning device 10 according to the embodiment of FIG. 2a, but without the rotating brush 24 in order to clearly illustrate the outer-most point 32 of the protruding member 33.

FIG. 3 illustrates a bottom view sequence a-f of movements of the robotic cleaning device 10 of the embodiment of the present invention as shown in FIG. 2 navigating into and out of two corners in a narrow corridor. In FIG. 3a, the robotic cleaning device navigates into the corner via a wall leading into the corner. The front end wall 17 of the main body faces the wall leading out of the corner while the left side wall 19 faces the wall leading into the corner. It should be noted that in practice, the front end wall 17 and side end walls 18, 19, are not flush against the walls of the corner to be cleaned, but the robotic cleaning device 10 is generally navigated such that they are located approximately 2-10 mm from the walls.

In FIG. 3b, the robotic cleaning device 10 is rotated such that the curved left side wall 19 follows the wall leading into the first corner while the front end wall 17 at one of its outer ends follows the wall leading out of the corner. Further, it can be seen that the protruding member 33 reaches all the way into the first corner, thereby enabling for the brush 24 to sweep debris out of the corner such that the cleaning member of the robotic cleaning device can remove the debris. The rotation continues in FIG. 3c, where the protruding member 33 practically is flush against the wall.

With reference to FIG. 3d, it can be seen that the protruding member 33 reaches all the way into the second corner, thereby enabling for the brush 24 to sweep debris out of the corner such that the cleaning member of the robotic cleaning device can remove the debris. In FIG. 3e, the robotic cleaning device 10 moves out of the second corner and finally in FIG. 3f, the cleaning device has made a 90-degree turn in the second corner and is ready to pursue the wall leading out of the corner or make another 90-degree turn.

Thus, as can be deduced from FIG. 3, the robotic cleaning device 10 according to the present invention advantageously navigates corners and difficult-to-access spaces like narrow corridors while still navigating very close to the walls leading into and out of the corners, thereby facilitating removal of debris from the floor at a very close range from the walls. The symmetry of the main body 11 further allows the robotic device 10 to take a corner from either a right or a left direction with the same cleaning effect, should the main body 11 be arranged with two protruding members 33

and brushes 24, one of each at each side of the front end wall 17. FIG. 4 illustrates still another embodiment of the present invention, where the robotic cleaning device 10 further comprises a flexible bumper 23. It should be noted that the greatest width A' of the main body 11 is at the same location in the front end portion 16 as for the embodiment shown in FIGS. 2a and b. Further, for illustrative purposes, the distance between the bumper 23 and the front end portion 16 is somewhat exaggerated; in practice the bumper 23 is arranged flush against the front end wall 17. In analogy with FIG. 2a, the lateral width A' from the right side wall 18 to the outermost point of the protruding member 33 is greater than the width B' taken from bumper 23 arranged at the front end wall 17 to the right side wall 18. The flexible bumper 23 covers at least the front end portion 16 of the main body 11, and extends in an embodiment of the present invention to the rotational axis of the drive shaft 14 on which the driving wheels 12, 13 are coaxially arranged. Thus, as long as the

robotic cleaning device 10 rotates or moves forward, the only part of the main body 11 that can run into obstacles is the bumper 23, implying that collisions with all obstacles can be detected by the bumper 23. Further, since the bumper 23 is flexible, it will press resiliently against the front end wall 17 when contacting obstacles, thus mitigating the thrusting effect it has on obstacles in its way and reducing the risk that the obstacles will be displaced, tip over and/or be damaged.

As previously mentioned, the robotic cleaning device 10 according to an embodiment of the present invention comprises obstacle detecting means, which in an embodiment are implemented by means of the bumper 23 being flexibly mounted to the main body 11. The bumper cooperates with one or more sensors (not shown) registering when the robotic cleaning device 10 runs against an obstacle thus causing pressing of the bumper 23 against the main body 11. The bumper 23 and the sensor(s) hence function as obstacle detecting means communicating with the microprocessor arranged in the main body 11 to control the cleaning device motor to rotate the driving wheels 12, 13 as required in view of navigation information received by the obstacle detecting means.

FIG. 5a shows still another embodiment of the present invention, where the robotic cleaning device 10 shown in FIG. 4 further is arranged with an indentation 25 or cut-in right behind the rotatable side brush 24. This is advantageous since the side brush 24 can reach around the periphery of smaller obstacles, such as chair legs 26, 27. Further, should the robotic cleaning device 10 comprise two side brushes, a respective indentation is arranged at the side brushes. The main body 11 of the robotic cleaning device 10 is arranged such that its width A is greatest laterally between the right side wall 18 and the left side wall 19 at the front end portion 16 of the main body, which is illustrated by means of the dotted line (i.e. the same width as that illustrated in FIGS. 2a and b). Thus, the width A is the greatest distance measured across the main body 11, advantageously facilitating navigation of corners. Hence, the width A is greater than or equal to width B defined from a rear end portion 20 of the main body 11 to the front end wall 17.

FIG. 5b shows how the robotic cleaning device according to the embodiment discussed in FIG. 5a moves such that first object 26 is placed in the indentation such that the side brush can each around and clean the first object 26. Thereafter, the robotic cleaning device moves towards a second object 27 and places it in the indentation such that cleaning around the second object 27 can be undertaken.

FIG. 6 shows a robotic cleaning device 10 according to a further embodiment of the present invention. In contrast to the embodiment shown e.g. in FIGS. 2a and b (when omitting the protruding member 33), the contour of the main body 11 of the robotic cleaning device 10 is in this particular embodiment asymmetric. The main body 11 of the robotic cleaning device 10 is arranged such that its width A" is greatest laterally between the right side wall 18 and the outermost point of the protruding member 33 on which the rotating brush 24 is arranged, which is illustrated by means of the dotted line. Thus, the width A" is the greatest distance measured across the main body 11, advantageously facilitating navigation of corners. Hence, the width A" is greater than or equal to width B" defined from a rear end portion 20 of the main body 11 to the front end wall 17.

The robotic cleaning device 10 according to the embodiment shown in FIG. 6 could further be arranged with an indentation 25 as previously discussed with reference to FIGS. 5a and b.

Even though the invention has been described with reference to specific exemplifying embodiments thereof, many different alterations, modifications and the like will become apparent for those skilled in the art. The described embodiments are therefore not intended to limit the scope of the invention, as defined by the appended claims.

The invention claimed is:

1. A robotic cleaning device comprising:
a main body having:

a wheel axis extending in a lateral direction,
a drive axis extending perpendicular to the wheel axis,
a front end portion located in front of the wheel axis,
a rear end portion located behind the wheel axis,
a first perimeter sidewall extending along and connecting the front end portion and the rear end portion on a first side of the drive axis,
a second perimeter sidewall extending along and connecting the front end portion and the rear end portion on a second side of the drive axis,
a laterally protruding member extending from the first perimeter sidewall along the lateral direction in the front end portion of the main body,
wherein the main body has a generally triangular shape defined by a width (A) and a width (B),
wherein width (A) is a greatest width of the main body as defined between an outermost point of the laterally protruding member and a point on the second perimeter sidewall located in the front end portion, and width (B) is a width of the main body as defined between the outermost point of the laterally protruding member and a point on the second perimeter sidewall located in the rear end portion, where width (A) is greater than width (B);

at least one driving wheel arranged on the main body on the wheel axis and configured to movably support the robotic cleaning device on a surface to be cleaned;
a cleaning member including an opening in the main body arranged at a bottom side in the front end portion of the main body for removing debris from the surface to be cleaned; and
a brush arranged at a bottom side of the laterally protruding member for removing debris from the surface to be cleaned.

2. The robotic cleaning device of claim 1, wherein the first perimeter sidewall and the second perimeter sidewall are curved.

3. The robotic cleaning device of claim 2, wherein the first perimeter sidewall forms a first arc of a circular shape and the second perimeter sidewall forms a second arc of the circular shape.

4. The robotic cleaning device of claim 1, wherein the main body comprises a front wall joining the first perimeter sidewall to the second perimeter sidewall in the front end portion of the main body, the front wall being generally straight.

5. The robotic cleaning device of claim 1, further comprising an indentation in the first perimeter sidewall behind the laterally protruding member.

6. The robotic cleaning device of claim 1, further comprising an obstacle detecting means arranged to detect obstacles and provide a control means with navigation information for enabling navigation of the robotic cleaning device.

7. The robotic cleaning device of claim 6, wherein the obstacle detecting means comprises a flexible bumper and at

least one sensor with which the flexible bumper is arranged to cooperate in order to register the robotic cleaning device contacting an obstacle.

8. The robotic cleaning device of claim 1, further comprising a bumper mounted to the main body and configured to press resiliently against the main body upon the robot cleaning device contacting an obstacle.

9. The robotic cleaning device of claim 8, wherein the bumper surrounds the front end portion of the main body.

10. The robotic cleaning device of claim 8, wherein the bumper extends from a first end located along the first perimeter sidewall proximate to the wheel axis, to a second end located along the second perimeter sidewall proximate to the wheel axis.

11. The robotic cleaning device of claim 8, further comprising one or more sensors configured to detect when the bumper presses resiliently against the main body.

12. The robotic cleaning device of claim 1, wherein the at least one driving wheel comprises a pair of coaxially arranged driving wheels mounted on the wheel axis, each driving wheel being located adjacent a respective one of the first perimeter sidewall and the second perimeter sidewall.

13. The robotic cleaning device of claim 1, wherein the brush comprises a rotating brush.

14. The robotic cleaning device of claim 13, wherein the rotating brush comprises radially extending arms that extend beyond an outer perimeter of the main body.

15. The robotic cleaning device of claim 1, further comprising a cleaning member extending along the bottom side of the front end portion of the main body, the cleaning member comprising one or more of a rotatable brush roll and an opening connected to a suction fan.

16. The robotic cleaning device of claim 15, wherein the cleaning member is arranged adjacent to the front end portion and at a location on the main body adjacent the greatest width of the main body.

17. The robotic cleaning device of claim 1, wherein the brush overlaps the opening of the cleaning member.

18. The robotic cleaning device of claim 1, wherein the laterally protruding member has an asymmetrical shape.

19. The robotic cleaning device of claim 1, wherein the drive axis is parallel to the front wall of the generally triangular shape.
